UNITED STATES PATENT OFFICE.

THOMAS J. McMAHON, OF ALBANY, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed January 4, 1923. Serial No. 610,560.

This invention relates mainly to sound-subduing cushion-supports for typewriting machines.

In carrying out the invention in one way, 5 I place upon the typewriter desk or table four supports upon which rest the four rubber feet of the typewriting machine, one support for each foot. Each support is preferably in the nature of a grating or net-work which is supported out of contact with the desk, the rubber foot of the typewriter resting upon said grating. To support the grating, there is employed an annulus or open frame, which may conveniently be 10 made in the form of a pine wood block having a central bore which is covered over by the grating. The grating may consist of wires which are stapled or otherwise firmly secured upon the top of the block, so as to 15 afford a firm support for the typewriting machine. The block may have a height of about one inch. When the rubber feet of the typewriting machine rest upon four gratings of this character, noise-producing vibration 20 of the desk top or leaf is greatly subdued. The grating may be of any suitable mesh, say six or eight meshes to the inch, and the wires may be under original tension. In any event, the weight of the typewriting ma- 25 chine tensions the wires, which is apparently a factor in preventing the conversion of the desk top into a sounding board.

The wire strands may extend over the top of the block, and the latter may be provided 30 with an annular cap or rectangular frame which may be made of wood and may cover all of the grating except the portion which extends directly across the opening in the block. This top frame not only covers the 35 unsightly borders of the wires and the staples that hold the same down, but also serves as recesses or sockets into which the rubber feet are caught, so that the typewriting machine cannot slide around upon the 40 desk top; the blocks being preferably screwed down upon the desk top before the caps are applied thereto.

When it is desired to place the typewriting machine upon a swinging leaf, such as 45 used in a common type of typewriter desks, springs may be employed, one at each side of the machine, for holding down the front portion of the typewriting machine upon the front noise-subduing supports above de- 50 scribed. The top end of the spring may be

connected to the upper portion of the front column of the machine frame at each side, and the spring may extend down along said column, and at its lower end may be caught into the wire grating. By this means the front of the machine is held against tipping upwardly or rearwardly when the leaf is 60 swung down and back into the desk. The caps on the blocks hold the typewriting machine from sliding down the leaf when the latter is rearwardly inclined. The weight of the machine is sufficient to prevent the rear end of the typewriter from jumping 65 out of the sockets or cups.

When it is desired to support a typewriter 70 desk or a sewing machine stand or the like upon the floor, in a manner to avoid a sounding-board effect of the floor itself, similar blocks may be used with similar wire gratings thereon; but they may be made of 75 larger proportions according to the burden to be borne. Such blocks need not necessarily be screwed to a floor, nor is it necessary to hold down the desk or stands by wire springs. Similar supports may be used un- 80 der pianos, phonographs and other musical instruments or apparatus where it is desired to prevent transmission of vibration from the instrument to the floor.

Other features and advantages will here- 85 inafter appear.

In the accompanying drawings,

Figure 1 is a view in side elevation, showing a machine in place upon the support of 90 the present invention.

Figure 2 is a perspective view of the support for one of the feet of the machine.

Figure 3 shows a modified form of one of the devices for anchoring the machine to the support.

On a platform 10, which may be the drop-leaf of a typewriter desk, are four blocks 11, one for each foot of the typewriting machine. The blocks 11 are hollow, as indicated at 12, and the blocks and the hollows therein may be of any desired shape. Set at each edge upon the top of the blocks and spanning the hollows therein are strings, preferably of metal wire and preferably interwoven in the form of meshes 13. These are shown as taut and as having the wires which compose the same soldered at the points 14 where they cross one another. Set upon each block and over the edge of the meshwork or grating thereon is a plate 15 105 110

having an opening 16 therethrough in registration with the hollow 12 in the block. This plate or annulus may be secured to the block by nails 17. By means of the nails 17, or by staples, or in any other suitable manner, the meshwork is held in place and under tension on the block between the same and the plate or annulus 15. The blocks are preferably anchored to the platform 10, and for this purpose bolts 18, having their heads 19 in countersinks 20 in the bottom of the platform, extend upward through the blocks and the plates 15 and are secured by nuts 21.

15 As shown in Figure 1, the feet 22 of the machine 23 are set up the meshworks clear of the blocks and of the plates 15. For holding the machine on its support, when the latter is a dropleaf, springs 24 are provided 20 at the front of the machine. These springs are under tension, and at their lower ends are caught in the meshes adjacent the front corner posts 25 of the machine. They extend vertically upward and have their upper 25 ends caught on the framework of the machine. In Figure 1 the upper end of the spring is shown as caught in an opening 26, which is found in the upper part of the side plate of the frame of an Underwood type- 30 writing machine. Any other suitable place or means of attachment for the spring to the machine may be provided. As hereinbefore stated, the springs 24 will hold the forward part of the machine to its support when the 35 drop-leaf is swung into the desk, and the weight of the machine will act to hold the rear portion thereof on the support. The plates or annuli 15 serve as abutments for the feet to prevent the machine from sliding off the supporting blocks when the drop-leaf is tilted, and to prevent accidental displacement of the machine from the supporting blocks at other times.

40 Instead of the springs 24, other means for holding the machine to the support may be provided. In Figure 3 a device for this purpose is shown comprising two rods 27 having hooks 28 at their ends; one of the hooks 28 to be caught in the mesh of the supporting block and the other to be caught onto the machine. The hooks 28 are threaded into and connected by a turn-buckle 29, so that after the hooks are in place the machine may be tightened down upon the supports.

45 Variations may be resorted to within the scope of the invention, and portions of the improvements may be used without others.

50 Having thus described my invention, I claim:

1. As a new article of manufacture, a sound deadening base block to be used as a support for the foot of a typewriter or like apparatus, said block being hollowed out and covered with an integral meshwork 65 superposed on the block, and means upon said meshwork and around the hollowed portion of the block for holding the meshwork to the block, said means extending into the block to hold the parts in assembled relation.

2. As a new article of manufacture, a sound deadening base block to be used as a support for the foot of a typewriter or like apparatus, said block being hollowed out 75 and covered with a meshwork of wire strands superposed on the block, a cap on the meshwork and extending around the hollowed portion of the block for preventing displacement of a typewriter foot and for holding the meshwork to the block.

3. A sound deadening base block to be used as a support for the foot of a typewriter or like sound emitting apparatus, said block being hollowed out and covered with an integral meshwork of wire strands soldered at their crossing points and superposed on the block, means upon said meshwork for holding the same to the block, said means surrounding the foot of the typewriter to prevent displacement, and being held to the block to retain the wire mesh extended across its top.

4. Supporting means for a typewriter or other sound emitting machine that has a plurality of feet comprising a tiltable support, a base block for each foot on which said foot is adapted to rest, each block being hollowed out and covered with meshwork, means extending above and around each of the meshworks to prevent the respective feet from sliding off the meshwork, and means extending through each block for holding the block to the support.

5. Supporting means for a typewriter or other sound emitting machine having a plurality of supports or feet, said means comprising a tiltable support, a base block for each foot on which said foot is adapted to rest, each block being hollowed out and covered with meshwork, a cap extending above and around the meshwork to prevent the displacement of the feet relative to the support, means for holding the cap to the block and the block to the support, and means attached to the typewriter and support to hold the typewriter on the blocks when said support is tilted.

THOMAS J. McMAHON.
